UNITED STATES PATENT OFFICE.

WILLARD F. RICHARDS, OF LANCASTER, NEW YORK, ASSIGNOR TO GOULD COUPLER COMPANY, OF NEW YORK, N. Y.

RAILWAY-CAR TRUCK.

965,600.

Specification of Letters Patent. Patented July 26, 1910.

Application filed April 10, 1909. Serial No. 489,032.

To all whom it may concern:

Be it known that I, WILLARD F. RICHARDS, a citizen of the United States, residing at Lancaster, in the county of Erie and State 5 of New York, have invented a new and useful Improvement in Railway-Car Trucks, of which the following is a specification.

This invention relates to railway car trucks of that sort in which the side frames 10 have bolster openings permanently closed all around, and are constructed to allow the ordinary bolster having permanently attached column guides to be inserted endwise into the bolster openings. The invention 15 is more particularly directed to improvements in the truck side frame of this sort disclosed in application for U. S. Letters Patent filed by me October 21, 1907, Serial No. 398,330.

The principal objects of the invention are 20 to reduce the weight and cost of side frames of this kind without sacrificing strength and rigidity; also to construct and combine the parts so that only two short bolts are required in each side frame to firmly and 25 securely retain the bolster guide in place on the side frame, while at the same time these bolts will be largely relieved from strain by interlocking portions of the guide and side 30 frame and cannot become disengaged from their holes in the event of the nuts being lost.

In the accompanying drawings, consisting 35 of two sheets: Figure 1 is a plan view, partly in section, in line 1—1, Fig. 2, and partly broken away, of a railway car truck bolster and frame embodying the invention. Fig. 2 is a side elevation thereof. Fig. 3 is a 40 fragmentary transverse sectional elevation thereof. Fig. 4 is a half elevation and half section of the spring plank and the bolster guide for one side frame. Fig. 5 is a fragmentary transverse sectional elevation of the 45 truck frame, omitting the bolster, in line 5—5, Fig. 2.

Like reference characters refer to like parts in the several figures.

Each side frame preferably consists of a 50 trussed frame or casting A which rests at its opposite ends on the journal boxes, and a tie bar a which is secured centrally to the depressed central portion of the casting A with its opposite ends extending beneath the journal boxes to which the ends of the casting A 55 and tie bar a are secured by the usual verti-

cal bolts. The casting A has an upper chord a'; a lower chord a² having a depressed horizontal central portion, and upright struts or bolster columns a³ which join the upper and lower chords and form with them a bolster opening to receive the end of the truck bolster. Preferably the upper chord a' is arched and of inverted U-shape in cross-section, while the columns a³ are of angle-shape 60 in cross-section with the lateral flanges projecting outwardly at the inner or adjacent edges of the columns, and the lower chord is also of angle-shape with the exception of that portion a⁴ thereof forming the bottom 65 edge of the bolster opening, which is of channel-shape or has upper and lower outwardly projecting flanges. This is a strong and desirable construction and is preferred from a manufacturing standpoint, 70 but the side frame could be of other construction.

B represents the spring plank or cross-piece which connects the depressed central portions of the two side frames at the opposite sides of the truck, and C the truck 80 bolster which is arranged with its ends extending through the bolster openings of the side frames and is yieldingly supported by springs D (indicated by broken lines) arranged in the bolster openings of the side 85 frames beneath the ends of the bolster. The spring plank B preferably consists of a channel beam arranged with its flanges projecting upwardly. A hollow cast steel bolster 90 having integral vertical column guides or lugs e at the opposite sides of its ends is shown, but the bolster may be of any ordinary construction having column guides 95 similarly arranged.

E E represent bolster guides which are 100 secured to the opposite ends of the spring plank and fastened in the bolster openings of the side frames and embrace the ends of the bolster between its column guides e, whereby the bolster ties the upper portions 105 of the side frames together and is guided in its vertical movements. Each guide has upright side pieces which are joined at their lower ends by the spring plank but are disconnected at their upper ends so that the 110 spring plank and guides form a sort of rack into which the bolster can be lowered vertically before the guides are secured in the side frames. The guides have horizontal base portions e which extend beneath the

ends of the spring plank and rest upon the lower edges a^4 of the bolster openings. The upright and base portions of the side pieces of the guide are riveted to the flanges and 5 bottom of the spring plank, as shown. The base portions e of the guides project horizontally beyond the inner and outer faces of the side frames and have depending flanges e' which straddle or interlock with 10 the lower edges a^4 of the bolster openings, whereby the lower ends of the guides are retained in position in the side frames and the two side frames are connected by the 15 spring plank. The upright side pieces of the guide are preferably of the same width transversely of the truck as the columns a^3 of the side frame and bear against the inner or adjacent sides of the columns and are 20 secured thereto by bolts f passing through holes in the upper portions of the side pieces 25 of the guide and the columns a^3 in the direction of the length of the side frame. The bolt holes f' in the side pieces of the guide are counter-sunk, see Fig. 4, to receive the 30 heads of these bolts f , and when the bolster is in place it is always supported by the springs between the heads of the bolts, as shown in Fig. 2, so that it would be impossible for the bolts to be disengaged from 35 their holes should the nuts work off of the bolts. The side pieces of the guide are formed with lips g , Figs. 1 and 4, which fit in seats g' formed in the columns a^3 at the inner side of the side frame. These lips g , bearing against the columns, relieve the bolts 40 from strains incident to the endwise thrusts of the bolster. Each guide is preferably made in two separate parts each including an upright side piece and part of the base e , as 45 thereby the guide will closely fit the spring plank notwithstanding possible slight variations in the dimensions of the spring plank and guides caused in making them, but each guide could, if desired, be made in a single integral U-shaped casting. The 50 lower portions of the upright side pieces of the guide are not subject to wear and are preferably reduced in thickness, as shown, to reduce the weight of the guide.

55 The bolster openings in the side frames are wider than the bolster measured over its column guides so that the bolster can enter the openings endwise. In assembling the parts, the bolster is first lowered into place between the upright sides of the guides before the latter are placed in the side frames. The guides with the bolster in place therein are then slipped into place in the bolster openings and secured by inserting 60 the bolts f , after which the bolster is lifted and the springs placed in position beneath its ends. The guides are of slightly less height than the bolster openings to enable 65 their lower ends to be interlocked with the bottom edges of the bolster openings.

I claim as my invention:

1. In a railway car truck, the combination of a bolster having side column guides, a side frame having a bolster opening which is closed at the top, bottom and sides and is of a width adapting the bolster with its column guides to be inserted endwise thereinto, a bolster guide which has upright side pieces disconnected at one end whereby the bolster can be placed in the guide with the side pieces of the guide embracing the bolster in engagement with its column guides, said guide being at one side of a width adapting it to be inserted laterally into said bolster opening and being formed at one end to interlock with the side frame, and means for securing the other end of the guide to the side frame, substantially as set forth. 75 80

2. In a railway car truck, the combination of a bolster having side column guides, a side frame having a bolster opening which is closed at the top, bottom and sides and is of a width adapting the bolster with its column guides to be inserted endwise thereinto, a bolster guide which has upright side pieces connected at their lower ends and disconnected at their upper ends whereby the bolster can be placed in the guide with the side pieces of the guide embracing the bolster between its column guides, said guide being at one side of a width adapting it to be inserted laterally into said bolster opening, and having parts at its lower end which interlock with the side frame, and securing bolts which extend through said upright 90 95 100 sides of the guide lengthwise of the side frame opposite to the bolster, substantially as set forth.

3. In a railway car truck, the combination of a bolster having side column guides, a side frame having a bolster opening which is closed at the top, bottom and sides and is of a width adapting the bolster with its column guides to be inserted endwise thereinto, a bolster guide which has upright side pieces connected at their lower ends and disconnected at their upper ends whereby the bolster can be placed in the guide with the side pieces of the guide embracing the bolster between its column guides, said guide being at one side of a width adapting it to be inserted laterally into said bolster opening and being formed at its lower end to interlock with the side frame and provided at one side of its upper portion with lips 105 110 115 adapted to bear against the side frame, and means for securing the upper portion of the guide to the side frame, substantially as set forth. 120 125

4. In a railway car truck, the combination of a bolster having side column guides, a side frame having a bolster opening which is closed at the top, bottom and sides and is of a width adapting the bolster with its column guides to be inserted endwise there- 130 135 140

into, a bolster guide which has upright side pieces disconnected at their upper ends whereby the bolster can be placed in the guide with the side pieces of the guide embracing the bolster in engagement with its column guides, said guide being at one side of a width adapting it to be inserted laterally into said bolster opening and having a base portion which interlocks with the side frame and projects beyond the inner and outer sides thereof, and means for securing the upper portion of the guide to the side frame, substantially as set forth.

5. In a railway car truck, the combination 15 of a bolster having side column guides, a side frame having a bolster opening which is closed at the top, bottom and sides and is of a width adapting the bolster with its column guides to be inserted endwise there- 20 into, a bolster guide which has upright side pieces disconnected at their upper ends whereby the bolster can be placed in the guide with the side pieces of the guide embracing the bolster in engagement with its column 25 guides, said guide being at one side of a width adapting it to be inserted laterally into said bolster opening, said side pieces of the guide being separate parts and each having a base portion which interlocks with the 30 side frame and projects beyond the inner and outer sides thereof, and means for securing the upper portion of the guide to the side frame, substantially as set forth.

6. In a railway car truck, the combination 35 of a bolster having side column guides, side frames having bolster openings which are closed at the top, bottom and sides and are of a width adapting the bolster with its

column guides to be inserted endwise there- 40 into, a spring plank, bolster guides which are secured to the opposite ends of said spring plank and have upright side pieces disconnected at their upper ends to embrace the bolster in engagement with its column guides, said guides being adapted to be in- 45 inserted laterally into said bolster openings and being provided at their lower ends with parts which interlock with the side frames, and means for securing the upper portions of said guides to the side frames, substan- 50 tially as set forth.

7. In a railway car truck, the combination of a bolster having side column guides, side frames having bolster openings which are closed at the top, bottom and sides and are 55 of a width adapting the bolster with its column guides to be inserted endwise there- 60 into, bolster guides which are adapted to be inserted laterally into said bolster openings and have base portions which interlock with said side frames and project beyond the inner and outer sides thereof, and upright 65 side portions which are disconnected at their upper ends to embrace the bolster in engagement with its column guides, a spring 65 plank secured at its opposite ends to said base portions of said guides, and means for securing the upper portions of said guides to the side frames, substantially as set forth.

Witness my hand, this 7th day of April, 70
1909.
